A. L. POWELL,
TRANSMISSION FOR ENGINES,
APPLICATION FILED DEC. 8, 1920.

1,384,342.

Patented July 12, 1921.

Inventor
A. L. Powell

UNITED STATES PATENT OFFICE.

ALVAH L. POWELL, OF MILES CITY, MONTANA, ASSIGNOR TO THE A. L. POWELL POWER CO., OF MILES CITY, MONTANA, A CORPORATION.

TRANSMISSION FOR ENGINES.

1,384,342.

Specification of Letters Patent. Patented July 12, 1921.

Application filed December 8, 1920. Serial No. 429,176.

To all whom it may concern:

Be it known that I, ALVAH L. POWELL, citizen of the United States, residing at Miles City, in the county of Custer and State 5 of Montana, have invented certain new and useful Improvements in Transmission for Engines, of which the following is a specification.

My invention relates to improvements in 10 the transmitting member of engines, by which I secure a variation in the movement of the piston with reference to that of the crank, enabling me to gain advantages in the operation of such engines that are not 15 possible with the constructions at present used. This application is one of a series, filed with it, bearing Serial Numbers 429,168; 429,170, to 429,175, inclusive, and covers improvements over the forms therein 20 shown, for, while the general principles are the same, the construction herein described includes a novel arrangement having advantages peculiar to itself.

In my prior application I have shown 25 transmitting means embracing a slotted yoke, and rollers acting on eccentrically disposed crank levers, the latter partially rotating by reason of the thrust of eccentric rollers in the slotted yoke. In my present 30 application I compensate for the angularity of movement of the toothed connecting rod by other means, and it is to this improvement that I confine my description. In the annexed drawing—

35 Figure 1 is an elevation, showing my invention attached to the piston of an engine, preferably of the internal combustion type.

Fig. 2 is a sectional plan, showing the arrangement of the segmental pinions on their 40 supporting pins.

The slotted yoke D^4 is attached to the piston A by a rod, A^1 , that may be integral with the aforesaid yoke, or be formed of a separate piece. The slot engages rollers, 45 A^2 , A^3 , mounted on pins, B^1 , B^1 , on crank levers B , B , the latter keyed to pins B^2 , B^2 , preferably mounted in the engine frame. The said pins B^2 , B^2 , also carry segmental pinions, E , E , keyed thereto. On the pins 50 B^2 , B^2 , are mounted smaller segmental pinions, B^6 , B^7 . Of these, the pinion B^6 is keyed to its pin, the pinion B^7 being freely rotatable. The loose pinion B^7 is held in position by a collar E^2 , Fig. 2.

55 From a crank on an engine shaft there is conventionally attached a crank rod, B^5 ,

toothed at its upper end (as shown in drawing), the teeth meshing with the segmental pinions B^6 , B^7 . These pinions are eccentrically set on the pins B^2 , B^2 . On the 60 downstroke of the piston A , the motion will be transmitted to the crank levers, by the action of the slotted yoke and rollers therein. This will cause the larger segmental pinions E , E , to move, partly rotating the 65 pins B^2 , B^2 . The smaller segmental pinions being in engagement with the rack end of the crank rod, B^5 , this will also move downward, causing the crank shaft to revolve. Normally, as the crank advances, the crank 70 rod would assume an angle other than that given in the drawing, and its position with reference to the segmental pinions engaged with it would alter; that is, the distance between the radii of the pitch circles of the 75 segmental pinions and of the rack would vary, but as the said segmental pinions are eccentrically mounted on the pins B^2 , B^2 , they will adjust themselves to this variation, the thrust of the slotted yoke being 80 evenly transmitted to the crank rod. It is evident, however, that the positive work will be done by the segmental pinion B^6 , for the reason that it is keyed to its pin, B^2 . The segmental pinion B^7 , not keyed, and 85 having an independent and free movement, will act as a supporting means, to hold the crank rod B^5 in proper relation to the positive segmental pinion B^6 .

What I believe is new and ask to have 90 protected by Letters Patent, is—

In a differential transmission member, the combination of pins, rocking levers mounted on said pins and keyed thereto, rollers on said levers, a yoke, slotted forks supported 95 by said yoke, means for engaging the said rollers in the slots of said slotted forks, a piston, a bar extending to said piston and connecting it with said yoke, a vertical crank connecting rod, toothed on opposite sides 100 and passing between said pins, a pinion mounted on and keyed to one of the pins, the teeth meshing with the teeth on the vertical connecting rod, a loose pinion mounted opposite to the before mentioned pinion and 105 meshing with the teeth on the vertical connecting rod, segmental pinions on said pins, meshing with each other, and a wrist pin holding the crank rod to the crank of an engine shaft, as hereinbefore described. 110

In testimony whereof I affix my signature.

ALVAH L. POWELL.
